UNITED STATES PATENT OFFICE.

A. HOAGLAND, OF JERSEY CITY, NEW JERSEY.

LOCK.

Specification of Letters Patent No. 19,564, dated March 9, 1858.

To all whom it may concern:

Be it known that I, ABRAHAM HOAGLAND, of Jersey City, Hudson county, in the State of New Jersey, have invented a new and 5 useful Improvement in Locks; and I hereby declare that the following is a full and exact description thereof.

To enable others to make my invention I proceed to describe its construction and operation, reference being had to the drawings hereunto annexed and making part of this 10 specification.

Figure 1 the works of the lock shown the cap being removed; Fig. 2 the face of the 15 lock, not showing the knob; Fig. 3 section; Fig. 4 edge view; Fig. 5 rear side of the lock with the cap on; Fig. 6 the bolt; Fig. 7 the quadrant tumbler; Fig. 8 diagrams of key, key-hole, &c.

20 The same letters refer to the same things in all the drafts.

A, the bolt. B, the quadrant tumbler. C, part of the key-hole case. D, the ward. E, the stem. F, India rubber spring. G, 25 shaft of the knob. H, cam of the lock. I, spring to hold the quadrant tumbler firm. J small stems to hold the quadrant tumblers when thrown back in unlocking. K, quadrant tumblers in separate parts, used when 30 it is required to complicate the lock. L, the key. M, the key holes, that on Fig. 2 is the outside one—that on Fig. 5, is on the inside of the lock, or outside of the door. N, a pin upon the bolt. O, a pin on the bed 35 of the lock.

The lock is intended more especially for a latch lock for doors—though it will serve for any of the ordinary purposes of a lock. It is adapted to a bed room, as it can be 40 locked inside with no key-hole extending to the outside, by which it could be unlocked.

The bolt is peculiar in form, having a wide slot in it for the application of an india rubber spring, F, (see Figs. 1 and 6). 45 This spring is a piece of vulcanized india rubber tube, strained tightly over a pin, N, upon the bolt and another pin, O, set or cast

firm in the bed of the lock. This spring is so situated that it can never fail to act.

The act of locking is performed by turning the quadrant tumblers, one or both to the position seen in Fig. 1, when they are held by the steel spring, I.

The bore of the quadrant tumbler, B, (see Fig. 8,) fits upon the partial cylinder, 55 C, within which is the stem, E, adapted to the key. The ward, D, is fixed to the cap, so that when the cap is put on the ward forms part of the partial cylinder, C. The key being put in the key hole, the bit of it 60 passes down one side of the ward, D, then, (in locking or unlocking,) across beneath the ward, and then out by the other side of the ward. For instance if the key in being put into the key hole, M, Fig. 2, with the 65 bit turned to the right it will raise the tumbler (in unlocking) and be drawn out of the key hole with the bit at the top. Then to lock it, the bit of the key is at top when entered and drawn out at the side. 70

The quadrant tumblers can be made single or of many parts, (see K, Fig. 8,) only one of which could be turned at a time. By varying the openings in them two or more keys might be required to open the lock— 75 that is, shove the bolt.

The outer lock, when required, can be managed from the inside, by a knob on the tumbler extending through the case of the lock. 80

I do not claim as original any one of the parts of this lock, but

What I claim as my invention and desire to secure by Letters Patent is—

The combination of the several parts to 85 form a catch lock with a separate key hole on each side, having the bolt, A, operated by the segments B, and the spring, F, constructed and arranged substantially as above described.

A. HOAGLAND.
